UNITED STATES PATENT OFFICE.

WILLIAM A. VIRGILS, OF CHICAGO, ILLINOIS, ASSIGNOR OF ONE-HALF TO CARL A. KREEGER,
OF CHICAGO, ILLINOIS.

MAIL-POUCH-DELIVERY DEVICE.

No. 884,782.

Specification of Letters Patent. Patented April 14, 1908.

Application filed December 2, 1907. Serial No. 404,800.

To all whom it may concern:

Be it known that I, WILLIAM A. VIRGILS, a citizen of the United States, residing at Chicago, county of Cook, and State of Illinois, have invented certain new and useful Improvements in Mail - Pouch - Delivery Devices, of which the following is a specification.

My invention relates to devices for handling mail pouches and particularly to devices for delivering the pouches from a rapidly moving train to a receiver located adjacent to the track at the point where it is desired to deliver the mail.

My invention will be more readily understood by reference to the accompanying drawings forming a part of this specification and in which

Figure 1 is a perspective view of a mail delivery device of the character mentioned, and embodying my invention in its preferred form, illustrating a portion of the mail car with that part of the device which is carried thereby and also the receiving crane, Fig. 2 is a perspective view of a portion of the device as viewed from within the car, and Fig. 3 is a perspective view of a preferred form of mail pouch especially designed for use with the mail delivery device embodying my invention.

Referring to the drawings, 1 indicates a portion of a side of a mail car and 2 a doorway therein. Secured to the car upon each side of the door is a bracket, 3 in which is rotatably and slidably mounted the pouch delivery crane. This comprises a straight bar portion, 4 which is mounted in the brackets, 3 an offset arm, 5 and a long arm, 6 arranged substantially parallel to the portion, 4. The arm, 6 is tapered towards its free end and at or near its opposite end is provided with a depressed portion, 7, forming a notch to receive the suspending member of the mail pouch. Fixed to the arm, 6 adjacent to the portion, 7 is a spring, 8. This extends, over the portion, 7 to retain the pouch suspending member therein and a considerable distance beyond in the opposite direction from that in which the train is moving, that is, toward the free end of the arm, 6. The spring is of sufficient strength to prevent accidental dislodgment of the pouch but permits easy detachment or removal of the pouch when engaged by the receiving crane to which it is to be delivered.

The crane is rotatably mounted in the brackets, 3 in order that the arm, 6 may lie close against the side of the car except when a pouch is to be delivered. When the train approaches a station at which a pouch is to be delivered, the crane is swung outwardly into a horizontal position, the pouch having first been secured to the arm, 6 beneath the spring, 8. To swing the crane outwardly, I provide the portion, 4 thereof with a handle, 9. The crane may be held in horizontal or operative position by the mail clerk but I prefer to provide suitable means for holding it. This comprises a bar, 10 slidably mounted in brackets, 11 secured to the inner walls of the car upon one side of the door. As soon as the crane is raised to horizontal position, the bar, 10 is slid longitudinally in the brackets until one end thereof extends over the handle, 9 which maintains the crane in operative position until it is retracted. 12 indicates a handle on the bar, 10 for operating the same and 13 a casting fixed to the inner end on the rod to prevent the same from turning in the brackets thus maintaining the handle, 12 in the proper position at all times.

The arm, 6 of the crane is preferably longer than the width of the car door, hence, in order that the mail clerk may readily place a pouch thereon, the crane is longitudinally slideable in the brackets, 3, a pair of stops, 14 and 15 limiting its movement in either direction. When the crane is pushed forwardly until the stop, 15 engages the bracket, 3, the end of the arm, 6 is in front of the door and readily accessible. As soon as the pouch is placed thereon, the crane is drawn back until the stop, 14 engages the bracket, 3. When the train approaches the station, the crane is raised into horizontal position, by the handle, 9 and the rod, 10 is drawn over the handle to maintain the crane in position.

The receiving crane comprises a long horizontally disposed arm, 16 which enters the suspending member of the pouch to withdraw it from the notch, 7, on the arm, 6, and a suitable stand-post for supporting the same. The arm, 16 extends parallel with the track and terminates in a forwardly and downwardly extending portion, 17, a return bend, 18 and an offset portion, 19, by which it is attached to the stand post, 20. The crane is adjustably secured to the stand post and to this end the portion, 19 terminates in

a downwardly extending portion 21, which telescopes within the post, 20. 22 indicates set screws for securing the crane at the proper height.

5 It is obvious that practically any style of mail pouch may be employed provided it is equipped with a suitable suspending device which may also be engaged by the receiving crane to remove it from the delivery crane on 10 the car. However, I prefer to form the mail pouch illustrated in Figs. 1 and 3 of the drawings. The pouch illustrated therein comprises a substantially cylindrical body portion, 23 which may be of leather or any suitable material and which is provided with a leather bottom, 24 riveted thereto. Secured to the top of the body portion is a bail, 25 by which the pouch is suspended from the crane arm, 6. The bail is formed of a steel rod and 20 is provided with a centrally disposed loop, 26 which is adapted to engage the notch, 7 in the arm, 6. The pouch is provided with a flexible closure, 27 which is riveted or otherwise secured to one side of the pouch for 25 closing the same. The closure, 27 is drawn tightly over the top thereof and fastened. To fasten the closure the body of the pouch is provided with a plurality of steel loops or 30 eyes, 28 which extend through corresponding eyelets in the end of the closure and a strap, 29 is passed through the loops and securely fastened. When the train reaches the receiving crane, the arm, 16 enters under the bail, 25 guiding the same into the downwardly inclined portion defined by the portions, 17 and 18 of the crane which quickly 35 removes the pouch from the delivery crane leaving it hanging at the bottom of the inclined portion.

40 Having described my invention what I claim as new and desire to secure by Letters Patent is:

1. In a device of the class described, a de-

livery crane mounted upon the side of a car and comprising a horizontal bar portion rotatably and slidably mounted in suitable brackets, an offset portion and a delivery arm substantially parallel with said bar portion, and a handle on said bar portion for raising said delivery arm into operative position, substantially as described.

2. In a device of the class described, a delivery crane mounted upon the side of a car and having a delivery arm extending parallel with the side of a car, said arm having a notch therein and a spring overhanging said notch, in combination with a mail pouch having a suspending member adapted to rest within said notch, and a receiving crane adapted to engage said suspending member, as and for the purpose specified.

3. In a device of the class described, a receiving crane comprising a stand-post and a receiving arm vertically adjustable thereon, said arm consisting of a horizontal portion 65 arranged parallel with the track a forwardly inclined portion, a return portion parallel therewith and an offset portion by which the device is secured to the post, substantially as described.

4. In a device of the class described, a delivery crane rotatably mounted upon the side of a car, a handle thereon for raising said crane into operative position, a sliding bar arranged upon the inner wall of the car for 75 engaging said handle, a handle on said bar for reciprocating the same and means for preventing said bar from turning, substantially as described.

In testimony whereof I have signed my name to this specification in the presence of two subscribing witnesses:

WILLIAM A. VIRGILIS.
